(57) **CLAIM**

The ornamental design for a timepiece face, as shown and described.

DESCRIPTION

FIG. 1 illustrates a front view of a timepiece face of the present invention; and,

FIG. 2 illustrates a front view thereof in an exemplary environment.

The broken lines in the Figures are for illustrative purposes only and form no part of the claimed design. The stippled shading of the upper right quadrant of the timepiece face in the Figures indicates a color contrast with the remaining quadrants, with neither the upper right quadrant nor the remaining quadrants being limited to any particular colors.
